UNITED STATES PATENT OFFICE.

THOMAS CROWLEY, OF LAMBERTVILLE, NEW JERSEY.

RUBBER BOOT AND SHOE.

No. 873,510.

Specification of Letters Patent.

Patented Dec. 10, 1907.

Application filed May 28, 1907. Serial No. 376,178.

To all whom it may concern:

Be it known that I, THOMAS CROWLEY, a citizen of the United States, residing at Lambertville, in the county of Hunterdon and State of New Jersey, have invented new and useful Improvements in Rubber Boots and Shoes, of which the following is a specification.

This invention relates to rubber boots or shoes, and the object thereof is to provide in a manner as hereinafter set forth a rubber boot or shoe whereby the heel is concealed and so secured in position as to prevent its being stripped off when coming in contact with a gunwale of a boat, rung of a ladder, or other obstruction.

A further object of the invention is to secure the heel in position in such a manner as to form a water-tight boot or shoe, and further to overcome the employing of metallic hold-fast devices for securing the heel in position. Such devices are objectionable as they scratch or mar decks or other surfaces.

A further object of the invention is to so secure the heel of a boot or shoe that it will not become loose when the boot or shoe is worn, which is often the case when the wearer straddles the gunwale of a boat or rung of a ladder, the wearer under such conditions bending the boot at the arch, the pressure exerted oftentimes causing the heel to separate from the shoe. To overcome this separation metallic hold-fast devices have usually been employed, but it has been found that the heel becomes loose, which will cause the boot to leak.

A further object of the invention is to provide a rubber boot or shoe with a concealed heel, the latter being so constructed as to not impair the arch of the shoe.

Further objects of the invention are to provide a rubber boot or shoe which shall be simple in its construction, water-tight, strong, durable, having a concealed heel, readily set up and comparatively inexpensive to manufacture.

With the foregoing and other objects in view, the invention consists in the novel construction, combination and arrangement of parts hereinafter more specifically described and illustrated in the accompanying drawings wherein is shown the preferred embodiment of the invention, but it is to be understood that changes, variations and modifications can be resorted to which come

within the scope of the claims hereunto appended.

In describing the invention in detail reference is had to the accompanying drawings wherein like characters denote corresponding parts throughout the several views, and in which—

Figure 1 is a sectional elevation showing the adaptation of the invention in connection with a rubber boot; Fig. 2 is a perspective view showing the inner sole and heel detached from each other, and, Fig. 3 is a longitudinal sectional view showing the parts forming the lower portion of the boot dis-assembled.

In the drawings is shown by way of example the adaptation of the invention in connection with a rubber boot, but it is to be understood that it is not limited to a rubber boot as it is also applicable to any form of over-shoe.

Referring to the drawings by reference characters, 1 denotes the leg portion, 2 the foot portion (these latter being provided with a lining 3), 4 the inner sole, 5 the heel block, 6 the filler, 7 the outer sole, and 8 the sole lining. The inner sole 4 has the heel block 5 cemented to the outer face thereof. The forward end of said block is beveled, as at 9, so as to preserve the arch of the boot 80 when the latter is completed, the beveled end 9 of the heel block projecting upwardly and forwardly at an inclination. The inner sole 4 is adapted to be positioned against the sole lining 8 after the lining 3 has the lower 90 portion thereof overlapping the sole lining, as at 10, the inner sole 4 retaining the overlapping portion 10 in position. When the inner sole 4, with the heel block 5 cemented thereto, is positioned in the manner as set 95 forth, the foot portion 2 is bent to overlap the forward part of the inner sole 4 in a manner well known in the art and such overlapping part is indicated by the reference character 11. The rear part of the foot portion 100 2, or what may be termed the heel counter, is of such length as to extend past the heel block 5. Such extending portion is then bent to overlap the heel block 5, as at 12. The lengthening of the heel counter so as to 105 overlap the heel block 5 acts as an additional means for securing the heel block to the inner sole 4. After the overlapping of the inner sole 4 and heel block 5 is had by the foot portion 2, the filler 6 is placed in position 110

- against the outer face of the heel block 5 and inner sole; the outer sole is then mounted upon the foot portion and cemented thereto, the outer sole being flanged as at 13 and completely incloses the lower portion of the boot. The outer sole 7 is of a contour so as to conform to the contour of the inner sole 4 with the heel block 5 attached, and by such arrangement the arch is preserved.
- 10 By setting up a boot in a manner as set forth, not only the outer sole acts as a means for securing the heel block to the foot portion 2 in connection with the cementing of the heel block 5 to the inner sole, but the overlapping portion of the heel counter further assists in the retention of the heel block in position. The outer sole 7 further acts as a means to form a water-tight boot owing to the fact that it completely incloses, after being cemented to, the lower portion of the boot. The inclosing of the heel block 5 by the outer sole 7 prevents the stripping off of the heel from the boot in case of the wearer meeting with an obstruction, and furthermore, it prevents the loosening of the heel block 5 when constantly bending the boot at the arch. The inclosing of the heel block 5 through the medium of the inner sole overcomes the necessity of employing metallic hold-fast devices for securing the heel block in position as is the case in the rubber boots now in general vogue.
- It is to be understood that the term "boot" in the claims is employed in a generic sense to cover a rubber boot, shoe or any other form of rubber foot wear.
1. A rubber boot comprising an inner sole, a heel block secured to the lower face of said sole at the rear thereof and having the forward portion thereof beveled, a filler positioned against the lower face of the inner sole, against the beveled portion of the heel and against the lower face of the heel block, a foot portion overlapping the heel block at the rear thereof and abutting against the rear end of the filler and further overlapping the inner sole at the front thereof and abutting against the forward end of the filler, and an outer sole inclosing the heel block and inner sole and overlapping and secured to the foot portion.
2. A rubber boot comprising an inner sole, a heel block secured to the inner sole, a foot portion overlapping the lower face of the inner sole and the lower face of the heel block, and an outer sole abutting against the overlapping part of the foot portion and overlapping and secured to the outer face of the foot portion.
3. A rubber boot comprising an inner sole, a heel block secured to the lower face of said inner sole at the rear thereof, a foot portion overlapping the lower face of the heel block and inner sole, a filler interposed between the edge of the overlapping part of the foot portion, and an outer sole abutting against the filler, the overlapping part of the foot portion, and overlapping and secured to the outer face of the foot portion.
4. A rubber boot comprising an inner sole, a heel block secured to the lower face thereof at the rear, said heel block having the forward portion thereof beveled, a foot portion overlapping the lower face of the heel block and inner sole, and an outer sole abutting against the overlapping part of the foot portion and overlapping and secured to the outer face of the foot portion.
5. A rubber boot comprising an inner sole, a heel formed of a single member and secured to the lower face of the inner sole at the rear thereof, said heel having the forward portion thereof beveled, a foot portion overlapping the heel and the inner sole, and an outer sole abutting against the overlapping part of the foot portion and overlapping and secured to the outer face of the foot portion.
- In testimony whereof I have hereunto set my hand in presence of two subscribing witnesses.
- THOMAS CROWLEY.
